UNITED STATES PATENT OFFICE.

JOHN J. CATRON, OF BONHAM, TEXAS.

FLUID-DISPENSING CONTROL.

1,301,385.

Specification of Letters Patent. Patented Apr. 22, 1919.

Application filed May 7, 1918. Serial No. 233,083.

To all whom it may concern:

Be it known that I, JOHN J. CATRON, a citizen of the United States, residing at Bonham, in the county of Fannin and State of Texas, have invented certain new and useful Improvements in Fluid-Dispensing Controls, of which the following is a specification.

This invention relates to new and useful improvements in fluid dispensing controls.

It is customary to place certain kinds of liquids in a main storage receptacle and to feed the same to a supplemental receptacle from which the fluid is elevated and discharged by means of compressed air through a suitable valve arrangement or control. It is this valve arrangement or control with which my invention has to do and the idea involved is to control the discharge of fluid and the supply of compressed air in a simple and efficient manner and with a minimum expenditure of air. It is further proposed to employ the expansive force of the air to elevate and discharge the fluid and to arrange the entire apparatus under direct control of the operator.

In carrying out the invention it is proposed to arrange a fluid discharge valve and to correlate with the same a compressed air supply valve both of which valves are connected with the receptacle from which the liquid is to be elevated and discharged, for instance such as is shown in my Letters Patent issued July 21st, 1914, No. 1,103,939. The valves are so arranged and timed that the discharge valve is opened in advance of the compressed air valve and remains open when the air valve is opened. The parts are arranged so that after the compressed air has been supplied the air valve may be closed without closing the discharge valve and thus the air under pressure which has been delivered is given an opportunity to expand and discharge the liquid through the discharge valve. A normally open air vent is associated with the valve arrangement and is arranged to be closed when the compressed air valve is operated and to be opened when the dispensing operation is completed in order to relieve the air pressure which might otherwise accumulate.

In a more specific embodiment of the invention I provide a discharge valve designed to be connected with the fluid discharge pipe from a storage receptacle and an air valve having connection with means for supply-

ing compressed air thereto and connected with a pipe leading to the said storage receptacle to which it supplies compressed air. These two valves are connected with a common operating member and arranged so that the fluid discharge valve opens in advance of the air valve and remains open during the entire open period of the air valve. Between the air valve and the means for supplying compressed air a cut off valve is disposed and correlated with the common operating member in such a way as to be open when the air valve is opened and to be closed when the air valve is closed. By this arrangement the air is positively cut off but the discharge valve still remains open. The air valve may also be arranged to admit compressed air in an increasing volume as it is opened, and by this means it is possible by slightly opening the air valve to cause a slow discharge of the fluid, but by opening the air valve to a point where a greater volume of air is admitted the discharge will be much faster. An air release valve is mounted adjacent the air valve and normally stands open to release any air in the pipe or tank below the air valve and this release valve or vent is provided with means of a simple nature which is operated to close said valve when it is desired to operate the other valves to discharge liquid. It is evident that where the air valve is opened to admit a considerable volume of air it may be closed and the liquid discharged by reason of the expansion of the air. Where it is desired to dispense only a small quantity of liquid it is obvious that only a slight opening of the air valve would be required, but where it was necessary to dispense a large quantity the air valve would be opened to its maximum point and after a quantity of the liquid had been discharged the air valve could be closed and the remainder of the quantity discharged by the expansion of the air and the whole dispensation quickly and accurately carried out. It is understood that when the desired amount of liquid has been discharged the discharge valve is cut off.

The invention will be more readily understood from a reading of the following specification and by reference to the accompanying drawings, in which an example of the invention is illustrated, and wherein—

Figure 1 is a view showing mechanism constructed in accordance with this inven-

tion, a portion being illustrated in vertical section and other portions in elevation,

Fig. 2 is a transverse vertical sectional view taken on the line 2—2 of Fig. 1.

5 Fig. 3 is a cross sectional detail of the air valve, and

Fig. 4 is a diagrammatical view showing the relative positions of the openings or passages in the discharge valve and the air valve.

10 In the drawings the numeral 1 designates a discharge pipe leading from a storage receptacle and 2 a compressed air supply pipe leading to the receptacle. The pipe 2 is connected with a sleeve 3 on which a discharge valve 4 is mounted. The discharge valve carries an elbow 5 which has connection with a trap 6 by means of a T-joint 7 from which the trap depends, while a discharge

15 connection 8 leads from the top of the part 7 and is provided with a coupling 9 by which it may be secured to a meter (not shown) or any other discharging medium. The part 3 has a lateral extension 10 which

20 25 rigidly supports a joint 11 to the lower end of which the pipe 2 is connected and which supports at its upper end an air valve 12. The discharge valve and the air valve are transversely alined. The discharge valve

30 35 has a tapered plug 13 provided with a socket stem 14 while the air valve has a tapered plug 15 provided with a socket stem 16. The stems 14 and 16 are adjacent and receive the square lugs 17 of an operating lever 18 disposed between the valves. By swinging this lever the valve plugs are rotated.

An angular connection 19 leads from the top of the air valve 12 to a cut off valve 20

40 45 which is connected with a source supplying compressed air and not shown. This valve 20 is of ordinary construction having a spring 21^a acting to seat a valve head 21 operated by a lever 22 which when depressed

50 55 pulls the valve head from its seat and when released permits the spring to seat the valve. The lever 22 has its end in the path of the rounded end 23 of the lever 18. It will be seen that normally the end 23 is not

55 60 in engagement with the lever 22 and thus said lever may be swung upward for a period without operating the lever 22 and without admitting compressed air to the valve 12. The plug 13 has a passage 24 ex-

65 70 tending therethrough while the plug 15 has a passage 25 extending therethrough very much smaller in diameter as will be obvious from Fig. 4. In the surface of the plug 15 a triangular duct 26 is disposed circumferentially with its deeper end at the passage. It will be seen that the plugs are so related

75 80 that the passage 24 of the plug 13 will be half opened or exposed before the tip of the duct 26 is brought under the opening

29 projects laterally from the connection 11 and is substantially the same in construction as the valve 20 being provided with a spring pressed valve (not shown) and an operating lever 31. The lever 31 has its end 5 penetrated by a rod 32 carrying a turn buckle 33 on its lower end and having connection at its upper end with a spring 34 suitably suspended. The tension of the 10 spring 34 is greater than the tension of the spring of the valve 30 so that the part 33 is pulled up against the lever 31 and the latter normally swung upward whereby the valve 29 is normally open thus permitting any air 15 in the pipe 2 and part 11 to escape. The part 33 has connection by means of a rod 35 with a suitable foot treadle (not shown) which when depressed pulls the parts 32 and 33 downward against the tension of the 20 spring 34 whereby the lever 31 is freed and the valve 29 permitted to seat. Thus when the operator is about to dispense liquid he must depress the connection 35 in order to close the valve 29 or the air would escape. 25 As soon as he completes the operation and relieves the pressure on the part 35 the spring 34 swings the lever 31 and opens the valve 29 thus releasing any accumulating air and at the same time providing a safety outlet which is automatic so far as its opening 30 operation is concerned.

What I claim is,

1. In a fluid dispensing control, the combination of a fluid discharge valve, an air 35 admitting valve correlated with the discharge valve, the discharge valve being arranged to open in advance of the air valve, the air valve being arranged to be opened and closed while the discharge valve is open 40 to admit a charge of compressed air and permit the same to expand to discharge a fluid through the discharge valve, and an air release valve arranged to normally stand open and to be closed when the air valve is 45 opened.

2. In a fluid dispensing control, the combination with an air admitting valve, a fluid discharge valve, and an air cut-off valve, or a common operating member connected with 50 the air admitting valve and the discharge valve, said member being mounted to travel a portion of its movement before operating the air cut-off valve.

3. In a fluid dispensing control, an air admitting valve, a fluid discharge valve, an air 55

cut-off valve, and a common operating member for all of said valves, in combination with an air release valve normally open, and means for closing said air release valve when said other valves are operated. 60

4. In a fluid dispensing control, the combination of an air admitting valve, a fluid discharge valve located opposite the air valve, the discharge valve having a passage such as to be opened in advance of the air valve and to 65 remain open during the open period of the air valve, an operating lever positively connected with the valves for operating the same in common, and an air cut-off valve in advance of the air admitting valve having 70 an operating element in position to be operated by the lever.

5. In a fluid dispensing control, the combination of an air admitting valve, a fluid discharge valve located opposite the air 75 valve, the discharge valve having a passage such as to be opened in advance of the air valve and to remain open during the open period of the air valve, an operating lever positively connected with the aforesaid 80 valves for operating the same in common, an air cut-off valve in advance of the air admitting valve having an operating element in position to be operated by the lever, and a spring closed air release valve beyond to the 85 air admitting valve, resilient means normally holding said release valve open, and means for overcoming said resilient means to permit the air release valve to close.

6. In a fluid dispensing control, the combination of a fluid discharge valve, a valve plug mounted in the discharge valve, an air admitting valve, a valve plug mounted in the air valve, the discharge valve plug having a passage considerably larger than the passage of the air valve plug, an operating lever connected with the valve plugs so as to be swung to rotate said plugs, the passage of the discharge valve plug being positioned to be opened during the initial movement of the 100 lever while the passage of the air valve plug remains closed, and an indicator associated with the lever showing the point in its movement at which the passage of the air valve plug opens, in combination with 105 an air cut-off valve arranged to be opened by the lever.

In testimony whereof I affix my signature.

JOHN J. CATRON.
